Primary Examiner — Vy N Koenig*Assistant Examiner* — Elizabeth Anne Glassberg(74) *Attorney, Agent, or Firm* — Adam Warwick Bell(57) **CLAIM**

The ornamental design for a protective field hood for dogs, as shown and described.

DESCRIPTION

FIG. 1 is a front and side perspective view of a protective field hood for dogs, showing my new design;

FIG. 2 is front view of the design;

FIG. 3 is a rear elevation view thereof;

FIG. 4 is first side view of the design;

FIG. 5 is a second side view of the design;

FIG. 6 is a top plan view thereof;

FIG. 7 is a bottom plan view thereof;

FIG. 8 is another side perspective view thereof, shown in an environment of use as worn by a dog; and,

FIG. 9 is another side perspective view thereof, shown in a second configuration with straps extended.

The broken lines showing the shape of a dog in FIG. 8 represent environmental subject matter that forms no part of the claim. The remaining broken lines shown in the drawings depict stitching on the protective field hood for dogs and form no part of the claimed design.
